UNITED STATES PATENT OFFICE.

MAX NOACK, OF FRIEDENAU, NEAR BERLIN, GERMANY.

METHOD OF RENDERING THE JOINTS OF THE CASEMATED PORT-HOLES OF WAR-SHIPS WATER-TIGHT.

1,039,316.

Specification of Letters Patent. Patented Sept. 24, 1912.

Application filed March 8, 1909. Serial No. 482,057.

To all whom it may concern:

Be it known that I, MAX NOACK, a subject of the King of Prussia, residing at Friedenau, near Berlin, Germany, have invented 5 certain new and useful Improvements in Methods of Rendering the Joints of the Casemated Port-Holes of War-Ships Water-Tight, of which the following is a specification.

10 This invention relates to a method and an arrangement for the packing of rifts in turret and casemate portholes.

The packings for this purpose heretofore employed have the disadvantage, that the 15 applying and removal of the same (both from the inside as well as from the outside) is attended with a great loss of time; while the application of the packing from the outside is a menace to human life.

20 It is the purpose of this present invention to obviate these drawbacks, and in order to accomplish this I provide a packing for the rifts of turret and casemate portholes which comprises an inflatable hose shoved into the 25 rift between the gun shield and the wall of the ship and inflated from the interior of the ship. If the packing so placed is to be removed the air or gas need only be let out of the hose and the packing can then be 30 pulled out of the rift without any difficulty.

The packing hose employed can consist either of one single piece, which is shoved into the rift in such manner that its ends overlap, or it can also consist of two pieces, 35 one of which can be advantageously secured for the packing of the lower part of the slit in the gun shield; while the other part can be employed for the packing of the upper and side parts of the rift, and is either secured to the wall of the ship or it can be 40 shoved into the rift inflated and taken out whenever it is desired to use the same; that is to say when the gun is ready for firing. After the air is let out of the hose secured 45 to the shield or the ship's side, the gun shield can then be turned around without hindrance.

In the drawing the object of the invention is represented in two embodiments.

50 Figure 1 shows the gun shield to which the new device is secured. Fig. 2 is a view seen from the top of Fig. 1. Fig. 3 is a section taken on line A—B of Fig. 1. Fig. 4 is a front view of the gun shield wherein the 55 packing device consists of two parts of hose.

Fig. 5 is a view seen from the top of Fig. 4, with partial section on line C—D of Fig. 4 at the height of the porthole. Fig. 6 is a sectional elevation taken on the line E—F of Fig. 4, and Fig. 7 is a section on line 60 G—H of Fig. 5.

Like numerals of reference indicate the same parts throughout the several figures in which:

1 indicates the gun shield, 2 the gun barrel and 3 the ship's side.

As will be seen from the drawing the packing of the rift of the turret or casemate porthole is accomplished by the shoving in the rift of a deflated air hose 4 from the inside of the ship between the gun shield 1 and the ship's side 3. The hose protected by suitable means against injuries is so shoved in that its ends 5 and 6 overlap. The closing of the hose is accomplished by the simple cementing of the overlapping ends. After the hose has been shoved into the rift it is inflated by means of an air pump or by introducing compressed air by means of a suitable valve 7 so that the hose when inflated at 8 and 9 provides a perfectly tight packing.

As is shown in Fig. 3 the packing device consists of the actual air hose 10 covered by a rubber cover 11, or the hose may be provided during its manufacture with a solid envelop (Figs. 6 and 7). Over the rubber coating 11 a water tight canvas envelop 12 may be advantageously arranged, the rubber as well as the canvas covering can be formed 90 in the shape of a hose, but in the embodiment shown in the drawing they are both represented as strips which are wound around the air hose and secured to the same by screw clamps or by other suitable means. 95

In the construction shown in Figs. 4 to 7, the packing device consists of two single parts, one of which packs the lower part of the rift of the turret or casemate porthole, and the other packs the upper and side parts 100 of the rift.

As will appear from Figs. 5, 6 and 7 a fixed canvas strip 13 is secured to the lower end of the gun shield 1 to which strip the canvas cover 12 is sewed or connected in 105 any other suitable manner. In this covering 12 the air hose 10 provided with a solid envelop is lodged. The covering 12 and the hose 10 extend to the ship's side, and after the inflation the ends 14 of the packing, the 110

part secured to the ship's side, as well as the loose shoved-in hose, pack at the ship's side at *a*.

Having thus described the several parts 5 of my invention what I claim as new and desire to secure by Letters Patent of the United States is:—

The combination of a gun-shield for closing the portholes in gun turrets or casemates in warships with an inflatable packing tube, said inflatable packing tube being 10 inserted in the rift between the porthole or casemate wall and the gun shield while the said inflatable packing tube is in a deflated

condition, said inflatable packing tube extending all around said gun-shield and overlapping at its ends, the said inflatable packing tube being caused by inflation to closely follow the form and contour of the parts in such manner as to completely seal the rift 15 20 in a watertight manner.

In witness whereof I have hereunto signed my name this 16th day of February 1909, in the presence of two subscribing witnesses.

MAX NOACK.
